UNITED STATES PATENT OFFICE.

SAMUEL W. PATTERSON, OF CHICAGO, ILLINOIS.

COMBINED BRACE AND SUSPENDERS.

SPECIFICATION forming part of Letters Patent No. 696,075, dated March 25, 1902.
Application filed August 2, 1901. Serial No. 70,684. (No model.)

To all whom it may concern:

Be it known that I, SAMUEL W. PATTERSON, a citizen of the United States, and a resident of Chicago, in the county of Cook and State 5 of Illinois, have invented certain new and useful Improvements in a Combined Brace and Suspenders, of which the following, when taken in connection with the drawings accompanying and forming a part hereof, is a 10 full and complete description, sufficient to enable those skilled in the art to which it pertains to understand, make, and use the same.

This invention relates to a combined brace and suspenders; and the object of the invention 15 is to obtain suspenders for trousers and skirts which may be worn over or underneath a shirt or shirt-waist, as preferred, for the purpose of holding trousers or skirts in position, and also for the purpose of obtaining 20 when desired a brace tending to draw and maintain the shoulders of the wearer back in position.

In the drawings referred to as forming a 25 part of this specification, Figure 1 is a perspective of a figure provided with an under-garment, shirt, or shirt-waist and trousers and a combined brace and suspenders embodying this invention, with a portion of the shirt-waist cut away to expose to view such 30 combined brace and suspenders; and Fig. 2 is a front elevation of the combined brace and suspenders with the several parts thereof in substantially the same position which is required when the same are to be donned 35 for wear.

A reference-letter applied to designate a given part is used to indicate such part throughout the several figures of the drawings wherever the same appears.

40 A'A' are adjustable loops, preferably made of the elastic woven fabric known in the art as "elastic" and attached together by adjustable connection B, which also is preferably made of elastic. The loops A'A' comprise, respectively, parts a' a², of elastic, metal loop C, (preferably bent up from wire,) and the sliding buckle C'. Parts a' a² are attached together at about the angle shown in Fig. 2 of the drawings and to the elastic D, (elastic 45 D forming a part of connection B,) as by the stitches d d. Part a is also attached to part

a², as at a³, and part a² is attached, at the upper end thereof, to loop C and at its lower end to buttonhole end a⁴. Buttonhole end a⁴ is provided with buttonhole a⁵. The part 55 a' is extended from its end which is attached to the elastic D through the sliding buckle C', to and through the loop C, and back to sliding buckle C', to one bar of which it is attached. The armholes afforded by the loops 60 A A', respectively, are thus made adjustable. The connection B is made adjustable, as by placing sliding buckle b between loops d' d² on the elastic forming connection B when taken in addition to elastic parts D D and attaching one end thereof to such buckle, as at b', the same connection as at C', and then extending the elastic around one bar of loop d', thence through sliding buckle b to loop d², to 65 one bar of which it is attached. Buttonhole 70 a⁵ may be worked into the lower end of part a², if preferred, instead of attaching what I have termed the "buttonhole part" a⁴ thereto.

In using the combined brace and suspenders embodying this invention the connection 75 B extends across the back of the person wearing them between the shoulders and well up toward the neck of such wearer, and parts a² a² extend down the sides of such person to a button, as e, Fig. 1, on trousers E. When 80 the suspenders and brace are to be worn underneath a shirt-waist, as, say, shirt-waist f in Fig. 1, a slot, as F, may be made in such shirt-waist on each side thereof, through which slots the end a⁴ may be drawn when 85 desired to be attached to button e. It will be found practicable, however, to wear the combined brace and suspenders embodying this invention over a shirt or shirt-waist when a coat is worn with no vest, as the position 90 thereof is such that it is not liable to be exposed to view.

This combined brace and suspenders may be used as a skirt-supporter for women and children, if desired.

95 In using this combined brace and suspenders the connection B may be adjusted by means of the sliding buckle b so that its function is merely to hold the suspenders upon the shoulders of the wearer, or, if it is desired, such connection may be adjusted so 100 that it may have the additional function of

tending to draw the shoulders of the wearer back, as a brace.

In wearing the combined brace and suspenders embodying this invention it will be found that great freedom of movement is afforded the body of the wearer, as in bending either forward or backward but little, if any, additional strain is put upon such combined brace and suspenders.

Having thus described my invention, what I claim as new, and desire to secure by Letters Patent, is—

1. In a combined brace and suspenders, an adjustable back connection of suspender fabric, fitting between the shoulders of the wearer thereof, suspender fabric attached to the ends of such back connection to extend upward over the shoulders and downward underneath the arms of the wearer, adjusting-buckles on the forward ones of such suspender fabrics, metal loops, around one bar of which, respectively, the suspender fabric provided with the adjusting-buckle extends and from thence runs back to the adjusting-buckle and is attached thereto, additional suspender fabric attached to the remaining bars of the respective metal loops, such additional suspender fabric provided with buttonholes at the lower ends thereof, and the suspender fabric extending downward from the ends of the back connection attached to such additional sus-

penders fabric at an angle thereto; substantially as described.

2. In a combined brace and suspenders, the combination of metal loops, C, C, d', d², adjustable shoulder-loops, A, A', of suspender fabric, an adjustable strap, B, connecting the shoulder-loops, and buttonhole ends, a⁴, a⁴, such shoulder-loops, respectively, consisting of suspender fabric a, a', and a², the suspender fabric a² attached to fabric a' by the metal loop C, the buttonhole ends a⁴, a⁴, attached to fabrics a², a², respectively, and the suspender fabrics a, a' attached together at an angle and, by means of metal loops d', d², attached to the adjustable connecting-strap B, the suspender fabric a of the shoulder-loop extending downward and forward and attached at an angle thereto to the suspender fabric a² between the metal loop C and the buttonhole end, a⁴, and the fabric a' of such shoulder-loop extending upward and over the shoulder of the wearer, through sliding buckle C', to and through the metal loop C and back to the sliding buckle C' and attached to one of the bars thereof; substantially as described.

SAMUEL W. PATTERSON.

In presence of—

CHARLES TURNER BROWN,
CORA A. ADAMS.
